DISCHARGE TUBE FABRICATION

Application filed December 12, 1927. Serial No. 239,417.

This invention relates generally to the fabrication of discharge tubes, and particularly to those discharge tubes including in final form a small quantity of a chosen gas to aid in the functioning of the tube.

A particular object of my invention is to speed up that part of the fabrication of discharge tubes involving the de-gassing of the included electrodes and disposal of the undesired expelled electrode gases, and to use the same period for other operations necessary to the production of the final successful discharge device.

My invention contemplates in particular the fabrication of a tube having one or more cathodes of the type depending for effective electron emission upon the aid of chemical compounds spread upon the surface of a suitable support adapted to be heated in a convenient way, and which compounds do not take on final form for best aid in the emission function until subjected to proper treatment within the tube. And it further contemplates in particular a type of such cathode that will not be injured by controlled ionic bombardment, but may be of such character that ionic bombardment can materially assist in securing an emissive surface having advantageous characteristics.

Another object is to employ ionic bombardment to aid in the conversion of chemical compounds and to bring about particular atomic arrangements within the molecules of such compounds.

Certain cathode compounds or coatings, such as the amphoteric compounds, having advantageous characteristics both in the matter of emission and preservation, are derived from different chemical compounds, or mixtures of them, cemented in raw form to the coating support, and do not take on final chemical composition and/or atomic disposition within the molecules to give the desired results until treated by heat and ionic bombardment in a highly evacuated tube, or in the presence of a small quantity of gas inert with respect to the particular cathode coating; that is, non-absorbable by the coating. There may however be deliberately present a quantity of selected gas intended for composi-

tion with some one or more of the elements of the raw chemical compounds of the original coating to form with such elements the final desired compounds.

So far as now understood these amphoteric and like compounds in activated form for good electron emission cannot be arrived at by ordinary chemical compounding, but only through conversion from certain selected compounds of different character with the aid of the processes herein outlined. The amphoteric compounds referred to are the salts of the combination of the oxides of the highly electro-positive metals, as for example, the alkaline and alkaline earth metal oxides with those oxygen compounds which may, by chemical conversion, be produced from amphoteric compounds, the resultant combinations being for example, aluminates, zincates, chromites, zirconates, etc. of the highly electro-positive metals.

One of the severest of the problems in the fabrication of discharge tubes is to so de-gas the included electrodes and dispose of the expelled gases that subsequently in use additional occluded or "getter bound" gas is not freed in sufficient amount to change the composition of the inert gas to detrimental degree if the tube is a so-called "gas filled" tube, or to alter the desired high degree of vacuum if the tube is a so-called "hard" tube.

This problem of subsequent gas appearance arises quite severely in the case of the employment of cathodes coated with the usual simple compounds, such as oxides of barium and the like, which cannot be formed in the usual brief period of the fabrication process usually employed with these simple compounds into final and permanent compounds, as is done in the case of the amphoteric compound cathode coatings with the process herein contemplated, and which incompletely formed cathodes therefore continue to change chemically during use with resultant gas freeing. The undesired freed gases have in general the detrimental effect of increasing the potential drop of the discharge path, resulting in a loss that reduces the efficiency of the device. A further bad result is a premature destruction of the electrodes.

I am aware that it has been proposed to de-gas electrodes of discharge tubes with the heat produced in such electrodes by electron or ion bombardment and pumping off the expelled gases. I am also aware of the method 5 of accomplishing the same result with the aid of heat produced in the electrodes by eddy currents generated under the influence of high frequency current fields. These prior methods however are time consuming and 10 have other disadvantages, in particular in the matter of treating the cathode to obviate subsequent gas generation or freeing.

According to the present invention tubes 15 can be freed so thoroughly of undesired gas during the fabrication process, and the cathode at the same time so formed that it will thereafter not yield gas to a disturbing degree, that the characteristics of the tube 20 will remain substantially constant over extended use, and if a gas-filled tube it can be expected to function in accordance with the degree and kind of gas used in the original filling. The process also provides for activating the cathode compound or compounds 25 for good and uniform electron emission over the entire surface after the desired chemical compound or compounds have been formed by the process.

The invention and its procedure will be 30 best understood by a description accompanied by reference to the figures of the drawing.

Fig. 1 illustrates the invention used in connection with the fabrication of a gas-filled 35 rectifying discharge tube provided with a single cathode and two anodes for ordinary so-called "full-wave" rectification.

Figs. 2, 3 and 4 illustrate modes of extension and modification of the processes as carried out in Fig. 1.

In Fig. 1 VT is an ordinary glass or like container provided with the usual stem N for carrying the connecting wires and supporting 45 the included electrodes. The electrodes are a filament F and two cooperating anodes A₁ and A₂, which combination of electrodes, properly connected to a source of alternating current, will produce in the completed tube 50 so-called "double wave" rectification. The tube is shown connected through a communicating stem E to a vacuum pump on one side and a source of inert or other desirable gas intended as a final gas filling if the tube is to 55 be a so-called "gas filled" tube, the two-way cock V providing for connecting either the vacuum pump or gas source to the tube as desired. The tube will be sealed off at the point J when the pumping and gas filling 60 features are completed.

There is shown attached to each of the anodes a "getter" substance K and K₁, respectively, such as magnesium, which substance 65 may be attached to the anode surface in any convenient way, such as welding. These

getter substances are preferably provided with projections P and P₁ extending in the direction of the filament, the reason for which arrangements will be later referred to.

Arrangement is made for heating the filament of cathode F by means of a secondary winding S₁ of a transformer of proper voltage characteristics, the switch W₁ providing for disconnecting the filament from the source. Arrangement is also made for supplying a potential between anodes A₁ and A₂ from secondary winding S₂ of a transformer, the switch W₂ providing for applying this potential as desired. A potential between the filament and both of the anodes is secured by means of the connection including the variable resistance R, the potential or degree of current being controlled by varying this resistance as required.

The filament F, or cathode, comprises a suitable support for a raw chemical compound, or mixture of raw chemical compounds, cemented or bound to the support in any suitable way, as by means of a cement or binder included in the mixture. Thus the chemical compounds may be in the form of a powder including gum-arabic or like binding material in sufficient quantity to cause the powder to securely adhere to the support, it being understood that this binder is of temporary character, it being usually intended in the forming of the type of cathode herein contemplated that this binder will be expelled during the processes when the forming of the final compounds results in a change of state of the raw compounds that includes a film adherence of the final compound to the support. Usually some material, not originally a binder, is included in the raw compound, which material has the property of transposing the final compounds into a more or less hard, firmly adhering coating on the surface of the support. It is usual to choose this material of such character as to either aid in producing the final desired compounds, or at least not to interfere with the electron emitting characteristics of them.

Proceeding with an outline of the process a tube, such as VT, would normally be connected to the vacuum pump through cock V and pumped while the filament F is heated by closing the switch W₁, the tube being at the same time heated in some suitable way to a temperature safely below that of softening of the glass or like material of the walls. This step therefore provides for expelling some of the occluded gases of the tube walls, filament and other physical elements while pumping is in progress, and ordinarily requires about 20 minutes before the desired exhaustion is arrived at. It should be pointed out that during this step the formation of the filament coating begins, this because the filament is heated as before stated. The heat is sufficient to volatilize the binding material of the

raw compounds, and the raw chemical compounds change over into an approximation of the final chemical compounds of the coating, which step also involves freeing of a large percentage of gases of conversion, but does not result in producing the final state of the coating necessary to active electron emission, which seems to be one of atomic arrangement within the molecules of the compounds. It is further pointed out that the coating does not arrive at a condition of being substantially non-gasing until this final condition of the compounds is arrived at.

At this point the tube is ready to be sealed off at the point J if it is not to have a gas filling, or the necessary desired gas for a gas-filled tube is admitted through cock V, the pressures of such fillings ranging in practice from fractions of one millimeter to a number of millimeters mercury, this depending upon the purposes and manner of use of the tubes, as well as their design.

If the tube is not to have a gas filling, but is to be a so-called "hard" tube, the next step in the process may be carried out with a gas filling and the tube later pumped to the desired degree of hardness before sealing off. However, the next step involves the use of ion bombardment in the presence of "getter", or getter alloy, materials which in themselves may be sufficient to produce the necessary ionic conditions to carry on the bombardment process without a gas filling. The absence of a gas filling however, introduces some difficulty in the matter of starting the discharge, it being first necessary to heat the getter substance to produce vapors at required pressures to sustain such a discharge. A further difficulty, in the absence of a gas filling, is that there does not exist a predetermined pressure around which to determine the necessary discharge potentials, and the initially low getter vapor pressures that might be created require undesirably high starting potentials, which high starting potentials may produce some destructive effects, particularly on the cathode, before they can be altered after the discharge is underway. Further, in depending upon getter vapor alone, precautions must be taken that there does not result an immediate condensing of the early production of getter vapors on cold walls and other parts of the tube, one precaution being to heat the tube and another being to produce the vapor quickly and in large quantities.

Though there are difficulties connected with producing the process with getter vapors alone these may be overcome in a manner to be later described.

If the process is to be continued in a manner that will permit sealing off the tube; that is the vacuum pump will not be further needed, the tube may be moved, after sealing off, to another work-bench at which arrangements are made for heating the filament by winding

S_1 and applying potentials between the anodes, and between such anode and the filament, by winding S_2 .

At the beginning of the application of the discharge potentials the projections P and P_1 of the getter substances K and K_1 receive the brunt of the bombardment, and therefore commence to heat and vaporize before the anodes A_1 and A_2 have reached sufficient temperature to commence to expel their occluded gases, as they later do. Immediately the getter vapors are produced they take part in the ionic discharge and, being ionized, are particularly aggressive in capturing and binding the undesirable occluded gases later released, so that this feature of having aggressive getter ions present the moment undesired gases appear is one of considerable importance. Also, it can be expected that the pumping process has not cleared the tube entirely of undesirable gases, so that the early production of the getter vapors provides for capturing these gases residual to the pumping process arrangement early in the bombardment stage.

This requirement accounts for placing the getter substance between the cathode and anode and making a projection thereon extending well towards the cathode.

The active bombardment in which the getter vapor partakes, once created, includes bombardment of the cathode coating with the result that the incomplete formation of the coating left over from the initial heating and pumping process is completed, including finally freeing the coating of all gases, which gases are immediately bound by the getter vapors. The bombardment also acts to activate the coating, that is, produce that final atomic arrangement within the molecules of the compounds necessary to final successful electron emissive characteristics.

A further advantage of the bombardment process is that in the formation of certain types of coating compounds there may be included in the gas filling a quantity of a gas or gases having elements needed to produce the final compound, so that during the bombardment process these elements may be conveyed thereby to the cathode coating to take their places in the final compound.

Another advantage of the bombardment process is that the bombardment results in producing the desired degree of heat immediately at the points in the coating where needed, and takes place more or less uniformly over the entire coating surface, thus avoiding heating other parts of the cathode structure to the same high temperatures required at the particular points in the coating. For example, if reliance should be had upon passing a current through the filament core to produce the necessary high heat at the surface of the coating to bring about the desired results in coating formation, it is

obvious that the temperature of the core would have to rise considerably higher than the required temperature at the surface of the coating, and also that this temperature would not be uniform throughout the extent 5 of the filament, because some parts of it are so positioned as to be able to dissipate heat faster than other parts.

The getter vapors progressively condense and deposit on the more or less cool walls of the tube VT, carrying with them the bound 10 undesired gases derived in the several ways before mentioned. The walls of a glass container form a good surface to which molecules of undesired gas cling, and do not readily leave under suction of the vacuum pump. The ions of getter vapors in depositing on the walls also capture and bind a large part 15 of these clinging molecules, and so occlude them in the condensation process, along with the gas molecules brought from other parts of the tube, that the occluded molecules are not thereafter free for later diffusion throughout the spaces of the tube.

20 A further advantageous result of the process is that during the condensation of the getter vapors the stem N, electrodes, shields and leads are electrically charged by the discharge producing potentials in such way as to produce about them fields which divert 25 the getter vapor ions, or are of such temperature that they do not invite condensation as readily as do the cool walls. The result is that when the process is discontinued these 30 parts of the tube are substantially free from the getter deposit, or mirror, thus avoiding short-circuiting paths with resulting possible flash over damages if these deposits were permitted to take place at these points of 35 the tubes which must later withstand operating differences of potential. For this reason the discharge process is maintained until the 40 getter condensation and deposition is completed, which completion is nicely indicated by a readily discernible change in the color 45 of the discharge readily recognized by an experienced operator of the process.

The electrodes, including the cathode, of the 50 tube must be designed so that the discharge can be increased until each electrode is heated sufficiently, and so maintained for a sufficient 55 long time, that the expulsion of the occluded gases is substantially complete. For this reason the cathode must be able to withstand without undue injury a greater current 60 than is ordinarily employed during the normal operation of the tube. In general the cathode current will be, during the operation herein outlined, from 1.5 to 2 times normal. 65 For this reason it is desirable to construct the portions of the inlead wires, particularly those portions imbedded in the stem, of such dimensions that they can safely carry this excess current. The other electrodes of the tube 70 should be so designed that they remain relatively cool under normal operating load conditions, but are sufficiently heated by the above mentioned overload for the expulsion of occluded gases during the gas expulsion process.

70 Fig. 2 shows a tube intended for the same service as the tube of Fig. 1, except that it includes a design and arrangement of electrodes particularly suitable for operating with high potential currents, and for which reason there is included a shield B between the anodes, which shield includes projections or extensions B₁, B₂ and B₃ for lengthening and directing the discharge paths. The arrangement of the electrodes is shown in perspective, 75 so that there is intended a second anode corresponding to anode A₁ located on the opposite side of shield B. It will be noted that the projection B₂ of the shield lengthens the path 80 between the two anodes around the right-hand side of the shield, that the same results from the extension B₃ around the left-hand side of the shield, and that the double extension B₁ lengthens the paths between the filament F and the two anodes.

85 In a tube so designed for high voltage operation special precautions are desirable in the matter of starting the bombardment operation, this because higher starting voltages are necessary, and since it cannot be expected that the gas filling will be entirely free from foreign gases still higher starting voltages may be necessary unless special arrangements are made to overcome the requirement. The 90 danger of a high starting voltage is that there may be concentrated on the cathode a severe bombardment that will do injury before the discharge can be controlled after starting takes place. This can be overcome by proper arrangement for having the necessary amount 95 of getter vapor present at the time the discharge commences.

100 There is shown attached to anode A₁, a piece of getter substance K₁ so formed as to more or less extend in the curved axis of the discharge path between the filament F and the anode A₁, which curved path is compelled in part by the projection B₁, but which is also due to the fact that the electron emission from the filament F flies out in all directions with the result that a part of the field occupies the upper regions of the tube beyond the limits of the projection B₁. It will be noted that with this long, curved discharge path between the filament F and the anode A₁, it is difficult to project the getter substance K₁ far enough to make as large a difference of potential between the end of the projecting getter and the anode as can be had in an arrangement such as shown in Fig. 1, so that there may not be sufficient concentration of the bombardment on the getter substance to the exclusion of the anode at the beginning of the discharge to free enough advance getter vapor to properly safeguard the operation against foreign gases.

either initially included in the gas filling or prematurely expelled from the electrodes, particularly the cathode which is highly sensitive to high voltage bombardment in the matter of gas expulsion.

5 For these reasons another source of getter vapor is illustrated, which is shown to include the getter substance K_2 interwoven or otherwise associated with a heating wire F_1 , which is connected to the outside of the tube in such way that heating from the secondary winding S_1 can be commenced before applying the discharge potential to the electrodes, thus making possible an adequate supply 10 of getter vapor at the commencement of the discharge. Once the discharge is properly and safely under way, the getter substance K_1 attached to the anode insures a further continued supply of getter vapor for the operation. After the tube is finished the outside connection to the heating wire F_1 can be cut off or otherwise disposed of.

Both the filament F and the heating wire F_1 are connected at one side to the shield B , so that a single leading in wire to this shield serves as one outside connection for both of these elements. The other ends of these elements have independent connections leading to the two branches of switch W_1 , which two branches may be closed independently to first start the getter vaporizing process and then to heat the filament at the commencement of the discharge. The discharge potentials are applied through switch W_2 from secondary 25 winding S_2 as in Fig. 1.

The springs D and D' , of conducting material, are shown connected between each side of the shield B and the wall of the tube, and therefore make a conductive connection between the shield, which is of a potential different from the anodes, and the metallic getter mirror deposited on the tube walls which connection is a path for relieving the charge constantly tending to collect on the walls 40 by reason of the electron or ion dispersion in the tube. Without such leak path it is possible for the tube walls to collect such a high charge that it will interrupt the discharge operation of the tube, and this effect 45 is enhanced by placing the hand or other object against the tube. Such interruption cannot occur with the leak paths provided by these springs, thus making the tube proof against interruption of operation by handling.

The contact made by such a spring with the getter surface is one of more or less high resistance, so that the relief of the tube wall charge is in the form of a leak, thus 50 maintaining some charge on the walls, but preventing an overload, and it may be found that in some types of tubes this maintained lower charge on the walls is of value.

60 The potential of the spring at its point of contact with the walls during the bom-

bardment process and getter depositing is such that it prevents a heavy deposit in the neighborhood of the spring, and this accounts for the automatically produced high resistance of this connection. Also, the deposit within the limits of the end turn of the spring is very thin, which therefore leaves what might be termed a "peep-hole" through which internal parts of the tube can afterwards be observed.

75 While one spring may be all that is necessary for providing the leak path between the shield and the walls, it is preferable to place a spring on opposite sides of the shield as shown to aid in supporting or centering the electrode structure in the tube, as opposed to a tendency of one spring to push this structure to one side.

80 Fig. 3 principally differs from Fig. 2 in the arrangement of the getter substance K_2 intended for early vaporizing. In this arrangement the getter substance is shown supported above the electrode structure in a position to be easily heated by eddy current effects from a high frequency coil L capped over the tube, which coil is suitably energized with high frequency currents from a suitable source Y . This arrangement provides for producing in the tube sufficient getter vapor in advance of starting the discharge to 85 satisfy the precautions outlined in connection with Fig. 2.

90 Fig. 4 shows another arrangement for early vaporization of an auxiliary getter substance K_2 . This auxiliary getter substance is shown positioned by means of a support quite close to the cathode F , and switch W , provides for independently producing a discharge potential between getter substance K_2 and the filament in advance of applying the main discharge potentials, so that getter substance K_2 can be vaporized by means of an auxiliary discharge between it and the cathode. There is also shown another getter substance K_3 located in close proximity to the cathode F , which will be vaporized by the heat of radiation from the filament at such times as may be helpful to the operation.

100 In tubes so designed as to produce cathode rays, it is also possible to bring about the vaporization of the getter material by so disposing the material in the tube as to be adequately under the influence of such rays.

105 While I have illustrated and explained my invention in connection with the fabrication of discharge tubes, and the formation of cathode coatings suitable for such tubes, yet the invention is one of broad application, particularly those features relating to the conversion of chemical compounds from one form to another with the aid of ion bombardment, and the inclusion of elements in the discharge gas which, by reason of the bombardment action, finally become constituent 110 elements of the desired compounds, which 115

features have general application obvious to those skilled in the art in chemical processes and production of desired atomic arrangements in such compounds.

Having thus described my invention, what I claim is:

1. A discharge tube comprising an anode and an electron emissive cathode, terminals for said anode and cathode including terminals for supplying heating current for the cathode, and a getter substance extending between said anode and cathode substantially shortening the initial discharge path therebetween, whereby the initial discharge potential between said anode and cathode is reduced and maintained at a low value during degasification of said tube.
2. A discharge tube comprising an anode and a coated filament, terminals for supplying heating current to said filament, a terminal for said anode, and a getter substance attached to said anode and extending therefrom a substantial portion of the distance between said anode and cathode along the normal discharge path therebetween.
3. The combination of a discharge tube, a cathode structure in said tube, a getter deposit on an internal wall of said tube, and a flexible conductor connected to said structure and in contact with said deposit, the deposit being less dense near the area of contact than on the remainder of said wall, thereby forming a high resistance contact between said deposit and said conductor.
4. The process of manufacture of thermionic discharge tubes, comprising the steps of coating the cathode with a mixture of the raw materials to form an emissive coating by chemical conversion, assembling said cathode with other electrodes of said tube, sealing the assembled electrodes within an envelope, substantially evacuating said envelope, heating said envelope and said cathode while continuing said step of evacuation, producing a getter vapor within said envelope, energizing the electrodes whereby a discharge occurs therebetween and ions are produced within said discharge path and the electrodes are bombarded thereby, concentrating said bombardment at the commencement of the discharge upon a getter substance so located and electrically charged as to attract said bombardment whereby said last mentioned getter substance is heated to a vaporizing temperature, and continuing the step of energization of said electrodes until substantially all of said getter material sublimates out of said discharge.
5. The process of manufacture of thermionic discharge tubes, comprising the steps of coating the cathode with a mixture of the raw materials to form an emissive coating by chemical conversion, assembling said cathode with other electrodes of said tube, sealing the assembled electrodes within an envelope,

envelope, substantially evacuating said envelope, heating said envelope and said cathode while continuing said step of evacuation, introducing an inert gas of predetermined pressure within said envelope producing a getter vapor within said envelope, energizing the electrodes whereby a discharge of overload intensity occurs therebetween and ions are produced within said discharge path and the electrodes are bombarded thereby, concentrating said bombardment at the commencement of the discharge upon a getter substance so located and electrically charged as to attract said bombardment whereby said last mentioned getter substance is heated to a vaporizing temperature, and continuing the step of energization of said electrodes until substantially all of said getter material sublimates out of said discharge.

6. The process of manufacture of thermionic discharge tubes, comprising the steps of coating the cathode with a mixture of the raw materials to form an emissive coating by chemical conversion, assembling said cathode with other electrodes of said tube, sealing the assembled electrodes within an envelope, substantially evacuating said envelope, heating said envelope and said cathode while continuing said step of evacuation, producing a getter vapor within said envelope, energizing the electrodes whereby a discharge occurs therebetween and ions are produced within said discharge path and the electrodes are bombarded thereby, concentrating said bombardment at the commencement of the discharge upon a getter substance so located and electrically charged as to attract said bombardment whereby said last mentioned getter substance is heated to a vaporizing temperature, and continuing the step of energization of said electrodes until substantially all of said getter material sublimates out of said discharge.

7. The process of manufacture of thermionic discharge tubes, comprising the steps of coating the cathode with a mixture of the raw materials to form an emissive coating by chemical conversion, assembling said cathode with other electrodes of said tube, sealing the assembled electrodes within an envelope, substantially evacuating said envelope, heating said envelope and said cathode while continuing said step of evacuation, producing a getter vapor within said envelope, energizing the electrodes whereby a discharge occurs therebetween and ions are produced within said discharge path and the electrodes are bombarded thereby, concentrating said bombardment at the commencement of the discharge upon a getter substance so located and electrically charged as to attract said bombardment whereby said last mentioned getter substance is heated to a vaporizing temperature, and continuing the step of energization of said electrodes until substantially all of said getter material sublimates out of said discharge.

8. The process of manufacture of thermionic discharge tubes, comprising the steps of coating the cathode with a mixture of the raw materials to form an emissive coating by chemical conversion, assembling said cathode with other electrodes of said tube, sealing the assembled electrodes within an envelope, substantially evacuating said envelope, heating said envelope and said cathode while continuing said step of evacuation, introducing an inert gas of predetermined pressure within said envelope producing a getter vapor within said envelope, energizing the electrodes whereby a discharge of overload intensity occurs therebetween and ions are produced within said discharge path and the electrodes are bombarded thereby, concentrating said bombardment at the commencement of the discharge upon a getter substance so located and electrically charged as to attract said bombardment whereby said last mentioned getter substance is heated to a vaporizing temperature, and continuing the step of energization of said electrodes until substantially all of said getter material sublimates out of said discharge.

step of energization of said electrodes until the chemical conversion of the raw materials upon the cathode and activation of the resultant product are completed and further extending and continuing the step of energization of said electrodes until substantially all of said getter material sublimates out of said discharge.

8. A discharge tube having electrodes therein, terminals for said electrodes, a getter substance attached to one of said electrodes and projecting along the discharge path between said electrodes to be subjected to a discharge therebetween, whereby the initial discharge path is substantially shorter than the normal discharge path between said electrodes, additional getter substance in said tube independent of said electrodes, and means for heating said additional getter substance independently of a discharge between said electrodes.

9. A process for the capture by getter vapors of undesired gases from the electrodes of a discharge device, the method of assuring a supply of ionized getter vapor at the commencement of ionic bombardment from a discharge, and the method of supplying a getter vapor for participation in the discharge which consists of heating a getter substance to vaporizing temperature in advance of initiating a discharge, initiating the discharge and concentrating the bombardment at the commencement of the discharge upon a getter substance so located as to produce such concentration, whereby the last mentioned getter substance is first heated to a vaporizing temperature.

10. A process for the capture by getter vapor of undesired gases from the electrodes of a discharge device one of which is a heatable electron-emissive cathode which has been partially degassed, which consists in first heating the cathode, then initiating a discharge between the hot cathode and another of said electrodes, concentrating the bombardment at the commencement of the discharge upon a getter substance so located as to produce such concentration, whereby the getter substance is first heated to vaporizing temperature, and continuing the discharge with continued vaporization of the getter substance co-incident with the evolution of gases from the electrodes.

11. A discharge tube having an anode and a cathode therein, terminals for said electrodes, a getter substance disposed between said anode and cathode and adapted to be vaporized by a discharge therebetween, additional getter substance in said tube independent of said anode and cathode, and means for heating said additional getter substance independently of a discharge between said anode and cathode.

CARL J. R. H. von WEDEL.
